UNITED STATES PATENT OFFICE.

JOHN H. FITZGERALD, OF FRANKFORT, WEST VIRGINIA, AND MARIA A. GAUGH, OF NEWPORT, KENTUCKY.

CURTAIN-FIXTURE.

SPECIFICATION forming part of Letters Patent No. 518,918, dated April 24, 1894.

Application filed June 20, 1893. Serial No. 478,243. (No model.)

To all whom it may concern:

Be it known that we, JOHN H. FITZGERALD, residing at Frankfort, county of Greenbrier, State of West Virginia, and MARIA A. GAUGH, residing at Newport, county of Campbell, State of Kentucky, have invented certain new and useful Improvements in Curtain Fixtures, of which the following is a specification.

10 The object of our invention is to provide a curtain supporting bracket which can be taken down and put up with the curtain rod and curtain draped thereon by a person standing on the floor, avoiding the use of steps or ladders.

15 Another object is to make a neat ornamental device on which the curtain rods are hinged so as to swing outward away from the windows in order that the windows can be washed or cleaned without taking down the curtains if desired.

20 The features of our invention are set forth in the description of the accompanying drawings making a part of the specification, in
25 which—

Figure 1 is a perspective elevation of a curtain and bracket in position as used. Fig. 2 is a detail sectional plan view, omitting the curtain and a portion of the curtain rod support. Fig. 3 is a detail plan view of the rotatable rod-support and the adjustable curtain rod. Fig. 4 is a detail sectional view of the lower bracket support. Fig. 5 is a sectional perspective view of a modified construction; and Fig. 6 is a detail perspective view looking at the under side of the rotatable rod support exhibited in Figs. 1, 2 and 3.

30 In the drawings, A indicates the side of a window frame, B the window sill, and C the top of the frame.

40 D represents the bracket on which the curtain rod *g'* is supported.

E represents a rotatable support adapted to support the curtain rod, and having a plate *i* resting on the bracket *D* and connected therewith by a pivot which journals in said bracket. The rotatable rod support is preferably provided with an ornamental cap or knob *b*, and the curtain rod has a sliding connection with
45 the rod support, whereby the curtain rod may

be adjusted to suit the conditions required for windows of different width.

We have shown two forms of extension rods. In Fig. 3 *c* represents a rod support, *g'* a tube fitting and sliding thereon. In Fig. 5 the knob *b* is provided with a hole and the curtain rod rests therein and may slide out or in to correspond with the width of window, *h* represents a set screw for holding rod *g* in any adjusted position.

60 The bracket is designed to be held rigidly with its arm projecting out into the room at right angles to the frame of the window. This is accomplished by means of the angular socket strap *H* into which the top of the bracket projects and is held.

I represents a stud affixed to the window frame above the window sill. It is provided with a recess or orifice *i'* in which the foot of the bracket rests.

70 *K* represents a handle attached to the leg of the bracket.

L represents the window curtain, *M* a cord attached to the curtain rod so as to enable a person standing on the floor to swing the curtain outward away from the window.

75 To confine the rotary movement of the rotatable rod-support *E* within certain limits, the plate *i* may be provided with stops *m*, adapted to strike the bracket *D*. The stops *m* are preferably formed by providing a projecting segmental flange depending from the margin or periphery of the plate *i*, as clearly shown in Fig. 6.

80 Mode of operation: The curtain rod is adjusted on its hinge and the curtain draped on the rod, the socket strap *H* and stud *I* are fixed to the window frame. The operator takes hold of the handle *K* and the leg of the bracket, inserts the top of the bracket in the strap *H* and raises it up until the foot will enter the recess or orifice in stud *I*. Its weight will hold it in position.

85 We have shown only one bracket, but we preferably employ a pair, one attached to each jamb of the frame so as to have a pair of the curtains to each window.

90 Having described our invention, what we claim is—

1. The combination in a curtain fixture, of 100

a non-rotary bracket D, a curtain rod-support E having a rotatable plate pivoted to the bracket and provided with the stops *m* adapted to strike the bracket to limit the rotary motion of the rod-support, and a curtain-rod having a sliding connection with the rotatable rod-support, substantially as described.

2. The combination in a curtain fixture, of an angular socket H, a stud I, a bracket D adapted to engage the angular socket and having a leg for engaging the stud, a curtain rod

support having a rotatable plate pivoted to the bracket, and a curtain rod engaged with the rotatable plate, substantially as set forth.

In testimony whereof we have hereunto set our hands.

JOHN H. FITZGERALD.
MARIA A. GAUGH.
